UNITED STATES PATENT OFFICE.

ALBERT RICHARD JAMES WILKINSON, OF TWICKENHAM, ENGLAND.

VISE OR LIKE WORK-HOLDER.

1,312,011.

Specification of Letters Patent.

Patented Aug. 5, 1919.

Application filed August 15, 1918. Serial No. 250,026.

To all whom it may concern:

Be it known that I, ALBERT RICHARD JAMES WILKINSON, a subject of the King of England, residing at Twickenham, Middlesex, in England, have invented certain new and useful Improvements in Vises or like Work-Holders, of which the following is a specification.

This invention relates to work holding devices such as vises or like workholders and the like and has for its object to provide a workholder which can readily be adjusted together with the work held thereby.

In many cases, for example when oxy-acetylene or a like welding process is in progress, it is desirable that the operator should be free to use both hands and at the same time it is undesirable that the process should be stopped in order to shift the position of the work. The present invention enables the operator to turn the work without interrupting the welding or other process while enabling the work to be set at the outset in a position convenient to the performance of the operation.

According to this invention a member is so mounted on a fixed bracket that its angle of inclination relatively to the bracket can be adjusted and on the adjustable member is rotatably carried a vise or like workholder which can be rotated in either direction, irrespective of the position in which the adjustable member is set, by means of treadle-operated mechanism. The vise or the like is disposed on a table provided with a spindle rotatably carried on the adjustable member and a second spindle which is preferably horizontally arranged drives the first spindle through bevel gearing. The second spindle can be locked and this lock can be released and the spindle rotated in either direction by means of a treadle which actuates a pawl so that rotation can be imparted through these spindles to the table and vise mounted thereon. The reversal of the direction of rotation is brought about by throwing the treadle-actuated pawl from one side to the other of the axis of a toothed wheel mounted on the second spindle with which the pawl engages.

The invention may be put into practice in various ways but the accompanying drawings illustrate by way of example one

construction according to this invention. In these drawings:

Figure 1 is a front elevation of the adjustable work holder.

Fig. 2 is an end view with the gear wheels removed to show the operation of the treadle actuated pawl.

Fig. 3 is a plan.

Like letters indicate like parts throughout the drawings.

A member A of suitable construction is provided with a bracket arm A' by means of which it can be securely fixed to a work bench or the like. A curved arm B is so pivotally mounted on the fixed member A that this arm can be turned relatively to the member or bracket and fixed in any position. The arm B is attached to the flange C of a sleeve C' which is loosely carried on a short hollow shaft A² which projects laterally from the member A to which the shaft is fixed or with which it is formed integral. On the outer end of the hollow shaft A² is fixed a collar D whose inner face is provided with one or more inclined surfaces D' adapted to act as cams. Between these cam surfaces D' and the opposite flat face of the sleeve C' is arranged on the shaft A² a sleeve E which has one face formed flat to bear against the flat end of the sleeve C' while the other face has one or more inclines or cam surfaces E' adapted to engage the cam surfaces D' on the fixed collar D. The sleeve E is provided with a projecting arm E² on the end of which is a handle. The arrangement is such that by movement of the arm E² in one direction the arm B is freed and can be moved into any position about the hollow shaft A². When however the arm E² and the sleeve E is moved in the opposite direction the inclined cam surfaces E' and D' will so coact as to jam the opposite end of the sleeve E against the face of the sleeve C' whereby the arm B will be securely clamped in the position into which it has been moved. Abrupt shoulders E³, D³ on the sleeve E and collar D respectively limit the movement of the sleeve upon the shaft A'.

A spindle F is carried by the fixed member A within the hollow shaft A² and on the end of this spindle which projects par-

allel to the overhanging part of the arm B is mounted loosely a sleeve which carries integral with it a bevel wheel G and a toothed wheel H. The latter lies between the bevel wheel which is disposed at the end of the spindle F and the adjacent face of the fixed member A. Between the toothed wheel H and the member A is mounted a plate J which can slide vertically and transversely to the spindle F. This plate J is provided on one face with two projections J' adapted to engage the teeth of the wheel H in the manner shown in Fig. 2. When thus engaged the wheel H and the bevel wheel G are locked against rotation.

Rotation can be imparted to the wheels H and G by means of a pawl K which is pivotally carried at K' on one arm L of a two-armed lever pivoted at L' on the fixed member A. To the other arm L² of this lever and connected thereto by a link L³ is a treadle L⁴. The arrangement is such that when the treadle is depressed and the lever arm L² is pulled downward, the pawl K will move upward and engage the teeth of the wheel H and rotate this wheel and the bevel wheel G step by step. The pawl K is prolonged as at K² on the other side of its pivot point K' and weighted. The end of the pawl K is of greater width than the wheel H and a part of the face of the pawl thus lies as will be seen in Fig. 1 opposite and beneath one or the other of two downwardly directed parts or fingers J² of the sliding plate J. Thus as the treadle actuated lever L turns and lifts the pawl K the end of the latter will strike one of the fingers J² and lift the plate J so as to disengage the projections J' from the teeth of the wheel H which is thus left free to be rotated by the further movement of the pawl as it engages the teeth of this wheel. When the treadle is released and the lever L and pawl K drop back again the plate J also drops and engages by means of the projections J' the teeth of the wheel H which is once more locked in the position into which it has been rotated.

The pawl K can be moved from one side to the other of the axis of the wheel H so as to enable rotation to be imparted to this wheel in either direction at will. The shifting over of the pawl may conveniently be effected in the following manner. Extending between two opposed parts A³ A⁴ of the fixed member A is a rod M which as can be seen in Figs. 1 and 3 lies beside the pawl K. In the part A⁴ is an opening A⁵ in which is an upwardly directed pin A⁶ which extends only partially across the opening. Within this opening A⁵ lies a plate N on whose inner end is formed or carried a sleeve N' through which passes the rod M. The sleeve N' is a sufficiently loose fit on the rod M to permit of the plate N being lifted or

turned about the sleeve on the rod M to a sufficient extent to enable one or other of two holes N² formed in the plate N to be engaged with or disengaged from the pin A⁶. At one side of the inner end of the plate N is a notch N³ in which lies the pawl K. The arrangement is such that the plate N with the notch N³ serves to guide the pawl K and direct it so as to act on the teeth of the wheel H either on one side or the other of the axis of this wheel according to the position of the plate N. If it is desired to throw the pawl K over from the position in which it is shown in Fig. 2 so that it will lie and operate on the other side of the axis of the wheel H, the outer end of the plate N is lifted so as to disengage the inner one of the two holes N² in that plate from the pin A⁶ when the plate N can be pushed inward until the second hole N² engages the pin A⁶. The pawl K will then be shifted in the desired manner and retained by the notch N³ in the position necessary to bring about step by step rotation of the wheel H in the opposite direction when the treadle actuated lever L L² is operated.

The pivoted arm B carries at its end a sleeve B' which serves as a bearing for a spindle O which lies radially with respect to the axis of the spindle F and shaft A². On the inner end of this spindle O is a bevel wheel P which gears with the bevel wheel G while on the opposite or outer end of the spindle O is mounted a table Q. On this table is disposed in some suitable manner a vise or other work-holder. Conveniently the vise comprises jaws R and R' which can slide on the table Q and are operated by a right and left-handed screw-threaded rotatable rod S (Fig. 3) the ends of which are carried by the table Q. The construction and operation of the vise may vary, but conveniently the jaws R R' are arranged to be reversible so as to enable articles to be held either by causing the jaws to approach each other or to move apart. The vise jaws also are preferably so formed and arranged as to enable them to be used for holding work whose dimensions exceed those of the table Q so that the latter may be made relatively short.

When step by step rotation is imparted to the toothed wheel H and bevel wheel G by operation of the treadle lever L L² and pawl K similar step by step rotation will be imparted to the table Q and vise R R' thereon and this rotation will take place in either direction according to the setting of the pawl K. It will be seen that as this rotation is brought about by means of a treadle both hands of the operator are left free and he can turn the work without stopping the operation on which he may be engaged. Further by reason of the relative disposition of the spindles O and F in relation to the

hollow shaft A² about which the arm B can be turned, rotation can in this manner be imparted to the vise carrying table Q irrespective of the position in which the arm B may be set about its pivot axis. Thus the table Q carrying the work held in the vise jaws R R' can be first set at a convenient angle for the necessary operation to be performed and then while this operation 5 is in progress and without interrupting it the table can be rotated in which ever direction is convenient.

When the table is not being rotated by means of the treadle-actuated mechanism it 10 is held against further rotation by the locking of the wheel H by means of the projections J' on the plate J in the manner above described. In this way the free rotation of the table Q is prevented but if it is desired 15 to rotate it freely when starting an operation or setting the work initially the plate J can be lifted by the finger so as to release the wheel H.

The details of construction may be modified as found desirable and in order to adapt 20 the device for the particular purpose for which it is to be used. Since the device is constructed throughout without the need for employing any spring or other part likely to 25 deteriorate or be damaged by heat and as all the parts can be simply formed the apparatus is particularly adapted for use for holding work which is being subjected to a welding operation when the work holder and 30 parts connected thereto are liable to become 35 considerably heated. When the work is once set for a welding operation with the arm B inclined into the convenient position, the operator can rotate the work without in- 40 terrupting the operation as he has both hands free. The continuance of the work without interruption is of especial importance in electric welding operations in which the present invention is therefore particu- 45 larly useful.

What I claim as my invention and desire to secure by Letters Patent is:—

1. In a work holding device the combination of a fixed bracket, a member so mounted 50 on the bracket that its angle of inclination relatively to the bracket can be adjusted, a member rotatably carried on the adjustable member, means for mounting work on the rotatable member, and treadle operated mechanism by means of which the rotatable member can be turned in either direction irrespective of the angular position of the adjustable member as set forth.

2. In a work holding device the combination 60 of a fixed bracket, a member so mounted on the bracket that its angle of inclination relatively to the bracket can be adjusted, a member rotatably carried on the adjustable member, means for mounting work on the 65 rotatable member, treadle operated mecha-

nism by means of which the rotatable member can be turned in either direction irrespective of the angular position of the adjustable member, means for locking the rotatable member against rotation, and means for releasing the locking device when the treadle mechanism is operated and the member is turned as set forth. 70

3. In a work holding device the combination 75 of a fixed bracket, a member so mounted on the bracket that its angle of inclination relatively to the bracket can be adjusted, a member rotatably carried on the adjustable member, means for mounting work on the rotatable member, treadle operated mechanism 80 by means of which the rotatable member can be turned in either direction irrespective of the angular position of the adjustable member, and means for automatically locking the rotatable member except 85 when the treadle operated mechanism is actuated as set forth.

4. In a work holding device the combination 90 of a fixed bracket, a member pivoted on the fixed bracket so that its angle of inclination relatively to the fixed bracket can be adjusted, means for locking the pivoted member after its angular position has been adjusted, a member rotatably carried on the pivoted member, means for mounting work 95 on the rotatable member, and treadle operated mechanism by means of which the rotatable member can be turned in either direction irrespective of the angular position of the pivoted member as set forth. 100

5. In a work holding device the combination 105 of a fixed bracket, a member so mounted on the bracket that its angle of inclination relatively to the bracket can be adjusted, a table mounted on a spindle rotatable in the adjustable member, means for mounting work on this table, a spindle rotatable in the fixed bracket, gearing between this spindle and the spindle on which the table is mounted, and treadle operated mechanism by 110 means of which the spindle carried in the fixed bracket can be rotated in either direction as set forth.

6. In a work holding device the combination 115 of a fixed bracket, a member so mounted on the bracket that its angle of inclination relatively to the bracket can be adjusted, a table mounted on a spindle rotatable in the adjustable member, means for mounting work on this table, a spindle rotatable in the fixed bracket, gearing between this spindle and the spindle on which the table is mounted, treadle operated mechanism by means of which the spindle carried in the fixed bracket can be rotated in either direction, 120 means for locking the table against rotation, and means for releasing the locking device when the treadle mechanism is operated and the table is turned as set forth. 125

7. In a work holding device the combina- 130

tion of a fixed bracket, a horizontal spindle carried by this bracket, a member pivoted about this spindle so that its angle of inclination relatively to the fixed bracket can be adjusted, means for locking the pivoted member after its angular position has been adjusted, a table mounted on a spindle rotatable in the pivoted member, gearing between the horizontal spindle and the spindle on which the table is mounted, means for mounting work on the table, a toothed wheel on the horizontal spindle, a treadle operated lever, and a pawl carried on this lever and adapted to engage the toothed wheel so as to cause rotation thereof when the treadle is operated as set forth.

8. In a work holding device the combination of a fixed bracket, a horizontal spindle carried by this bracket, a member pivoted about this spindle so that its angle of inclination relatively to the fixed bracket can be adjusted, means for locking the pivoted member after its angular position has been adjusted, a table mounted on a spindle rotatable in the pivoted member, gearing between the horizontal spindle and the spindle on which the table is mounted, means for mounting work on the table, a toothed wheel on the horizontal spindle, a treadle operated lever, a pawl carried on this lever and adapted to engage the toothed wheel so as to cause rotation thereof when the treadle is operated, and means for swinging the pawl from one side to the other of the axis of the toothed wheel so as to reverse the direction in which the table will be turned when the treadle is operated as set forth.

9. In a work holding device the combination of a fixed bracket, a horizontal spindle carried by this bracket, a member pivoted about this spindle so that its angle of inclination relatively to the fixed bracket can be adjusted, means for locking the pivoted member after its angular position has been adjusted, a table mounted on a spindle rotatable in the pivoted member, gearing between the horizontal spindle and the spindle on which the table is mounted, means for mounting work on the table, a toothed wheel on the horizontal spindle, a treadle operated lever, a pawl carried on this lever and adapted to engage the toothed wheel so as to cause rotation thereof when the treadle is operated, and a sliding member which is adapted to move automatically into engagement with the toothed wheel and to be moved out of engagement with this wheel by the pawl when the lever on which the pawl is carried is actuated by the treadle as set forth.

10. In a work holding device the combination of a fixed bracket, a horizontal spindle carried by this bracket, a member pivoted about this spindle so that its angle of inclination relatively to the fixed bracket can be adjusted, means for locking the pivoted member after its angular position has been adjusted, a table mounted on a spindle rotatable in the pivoted member, gearing between the horizontal spindle and the spindle on which the table is mounted, means for mounting work on the table, a toothed wheel on the horizontal spindle, a treadle operated lever, a pawl carried on this lever and adapted to engage the toothed wheel so as to cause rotation thereof when the treadle is operated, means for swinging the pawl from one side to the other of the axis of the toothed wheel so as to reverse the direction in which the table will be turned when the treadle is operated, and a sliding member which is adapted to move automatically into engagement with the toothed wheel and to be moved out of engagement with this wheel by the pawl when the lever on which the pawl is carried is actuated by the treadle as set forth.

11. In a work holding device the combination of a fixed bracket, a horizontal spindle carried by this bracket, a member pivoted about this spindle so that its angle of inclination relatively to the fixed bracket can be adjusted, means for locking the pivoted member after its angular position has been adjusted, a bevel wheel on one end of the horizontal spindle, a spindle rotatably mounted on the pivoted member, a table on one end of this spindle, a bevel wheel on the other end of this spindle gearing with the bevel wheel on the horizontal spindle, means for mounting work on the table, a toothed wheel on the horizontal spindle, a treadle operated lever, a pawl carried on this lever and adapted to engage the toothed wheel so as to cause rotation thereof when the treadle is operated, means for swinging the pawl from one side to the other of the axis of the toothed wheel so as to reverse the direction in which the table will be turned when the treadle is operated, and a sliding member which is adapted to move automatically into engagement with the toothed wheel and to be moved out of engagement with this wheel by the pawl when the lever on which the pawl is carried is actuated by the treadle as set forth.

In testimony whereof I have signed my name to this specification.

ALBERT RICHARD JAMES WILKINSON.
